UNITED STATES PATENT OFFICE.

MICHAEL J. STRZELECKI, OF EAST CLEVELAND, OHIO.

FIRE SHIELD.

Application filed February 27, 1926. Serial No. 91,094.

My invention relates to fire shields and particularly to shields adapted to be suspended above the fire in the fire pot of furnaces. It is an object of my improved 5 structure to enable the greatest possible amount of heat from combustion of fuel in fire pots to be retained in a particular zone of the space in these pots, permitting the lowest ratio of such heat to be lost by convection so far remote from the furnace walls 10 that much of the heat is carried out through the smoke tube.

It is a further object of my improved structure to provide my fire shield as a hood 15 form of shield which may be suspended in an inverted position over the central portion of the fire in the pot leaving a restricted annular space about the edge of the shield which directs the heated gas currents positively out around such edge thus directing 20 them against the walls of the fire pot and deriving the largest possible heat units from the fuel and heating the said walls for the purpose of heating the chosen agency for 25 conveying the units to the ultimate parts to be heated, such agency being easily either air or water, the action of the shield in economy of fuel in the fire pot, being similar in either case.

30 In the drawings accompanying and forming a part of this application—

Figure 1 is a central, vertical section of an inner wall of a furnace provided with an improved fire shield;

35 Figure 2 is a plan view of such a shield, and

Figure 3 is a detail view of a notched bar for suspending the shield adjustably from a bar above the fire.

40 The same part is designated by the same reference character throughout the several views.

Upon the grate 5 is supported the fuel 6 above the usual ash pot 7, the waist 8 being 45 shown as enveloping the flame section which, if unobstructed thereabove, would normally rise centrally in the fire pot directly towards the smoke flue 9 and a large proportion of the unburned carbon of what- 50 ever fuel is used, would pass out through such flue, both disagreeably blackening the atmosphere in the vicinity of the chimney and indicating a positive loss of heat to the consumer due to lack of full combustion of 55 the fuel carbons.

Much of the loss of heat units in the ordi-

nary fire pot, is due to the direct current of gases from the fuel centrally toward the smoke flue, as stated above; and this loss can very largely be neutralized by a novel and 60 improved shield suspended directly over the center portion of the fuel, leaving an annular space 10 about the shield edges so that the flame and burning gases will rise upward as before until prevented from rising directly 65 upward to a greater height, when the gases and flames will be directed radially outward, thus directing them against the inner surface of the furnace wall 11 which is just the desired result hoped for.

70 Numeral 12 designates the furnace section holding the fuel, 13 designates the fire dome, and 14 the hood directing the smoke and other light gases to the flue 15 leading to the chimney. I provide a shield 16 of fire clay, 75 certain metal elements being provided to suspend the shield over the fire, a staple 17 being attached to the shield and thereby forming a loop to which is connected the hook 18 of an elongated bar 19 having a series of 80 open notches 20 at the opposite end designed to be detachably hooked over a rod 21 suitably mounted above the dome 13 so that the bar carrying its attached shield may be adjustably positioned over the center of the fire 85 at proper distance above the same.

The shield is most advantageously made 90 of concavo-convex form and the staple 17 is properly attached to the convex surface so that the open concave surface 22 is directed 95 downward towards the fire. The shield will prevent the heat rays from moving directly upward but will make certain the radial direction of the said rays outward from the central portion of the shield against the 100 walls of the fire pot, as indicated by the arrows in Fig. 1 of the drawings. The larger the shield, the smaller the annular space between the shield edges and the furnace walls. An advantage of the convex form of the upper surface of the shield lies in the tendency of fuel falling upon it to slide off onto the fire, and the usual position of the fuel door 105 23 somewhat higher than the shield makes this tendency the more striking.

110 The rod 21 has one end flattened somewhat at 24 to receive therein the extension screw 25 acting reversely to the direction of the usual turn-buckle. By this means, the rod 21 may be mounted near the base of the hood 14 with one end extending into the flue 9, and secured in proper position by the screw.

While the shield has been described as formed or molded of fire clay, it is to be understood that I contemplate the use of other materials for the device, such as molded earthy materials, as for example, brick clay, asphaltum, concrete, or other minerals. If it is found desirable, iron or stone materials may be used for the purpose, it being known that ordinarily material that is not destroyed by intense heat, serves the purpose excellently of deflecting heat rays from the lower concave surface of the shield and directs them outward toward the furnace walls and permits the upward deflection thereof about the edges of the shield.

Operation.—In operation, the supporting rod 21 is mounted in the hood 14 of the furnace with one end extending into the smoke flue 9 and the other end extended against the inner surface of the hood wall, the screw device 25 being elongated with its upper end contacting the surface of the flue and the lower ends forced against the flat surface 24, so that the rod 21 is held in adjusted position adapted to the size and particular shape of the furnace interior and permitting ready mounting or removal of the rod. The bar 19 is then attached to the staple 17 of the shield 16 and the two parts attached to the interior of the furnace in the manner shown in Fig. 1. The notches 20 make vertical adjustment of the bar and shield attached thereto very convenient to accommodate the shield to both the amount of fuel in the fire pot at a given time, and also to the height of a particular furnace.

It is well known that much heat from concentrated fuel such as coal and coke, is ordinarily lost because of the large radius of the fire interior, the heat rays moving nearest the furnace walls being most effective in heating the vicinity immediately outside of such walls, whether such outer space be a chamber for air currents, a space for water currents, or other means of heat distribution. Therefore, the concentration of heat rays in the annular space nearest such walls will be most effective in resulting in economy of fuel. This I have effected by the centrally-mounted shield as above described.

While the specific construction of this invention has been shown and described, it is not confined thereto, as changes and alterations may be made therein without departing from the spirit of the invention as defined by the following claims.

What I claim is:—

1. In combination with a furnace having an upper hood portion and a smoke flue leading from the latter, a cup shaped plate of heat resisting material and a staple attached to the central convex surface of the said plate, an elongated rod having a flat end adapted to be inserted in the said flue, adjustable means within the flue for pressing

the flat end of the rod against the lower wall of the flue to support the rod over the fire in the furnace, an elongated bar having a hook at one end for engaging the staple of the shield to suspend the latter and having spaced lateral notches on one side of the bar inclined somewhat toward the said hook, for receiving the rod selectively therein.

2. In combination with a furnace and a horizontal smoke flue leading from its upper portion, a substantially circular plate of heat-resisting material having a concave surface on one side thereof, and a convex surface having a supporting staple therein, and means for adjustably suspending the plate at a slight distance above the central portion of the fire in said furnace, said means including a bar having a hook at one end for engaging said staple and a notched edge at the other end, a rod mounted horizontally across the furnace in alinement with the flue and engaging selectively the notches of the bar, and clamping means within the flue for detachably supporting the said rod.

3. In combination with a furnace having a smoke flue leading from its upper portion a shield of heat resisting material having a convex surface on one side, an elongated rod located above the combustion chamber of the furnace and extending into the smoke flue, means within the flue for detachably holding the rod in position, a staple secured to the convex surface of the shield, and a bar having a hook at one end for engaging the said staple to suspend the shield over the fire and a series of notches adjacent the other end of the bar and inclined toward the hook end for selectively engaging the said rod, so that the shield will be detachably mounted at varying distances from the fire.

4. In combination with a furnace having a smoke flue leading from its upper portion, a substantially circular plate of heat resisting material of concavo-convex form, the convex surface having a supporting staple therein, means for adjustably suspending the plate at a slight distance above the central portion of the fire in the furnace, said means including a bar having a hook at one end for engaging said staple and a notched edge at the other end, a rod mounted horizontally across the furnace in alinement with the flue and engaging selectively the notches of the bar, and having a flat end adapted to be inserted in the said flue, and a rotatable extension screw positioned detachably within the flue with one end pressing downwardly upon the flat end of the rod and the upper end pressing against the upper surface of the flue and provided with a polygonal head for actuating the screw.

In witness whereof I have hereunto set my hand this 22nd day of February, 1926.

MICHAEL J. STRZELECKI.
